METAL-DELIVERING PUMP.

1,289,235.

Specification of Letters Patent. Patented Dec. 31, 1918.

Application filed May 20, 1915. Serial No. 29,286.

To all whom it may concern:

Be it known that I, CONRAD NORDFORS, a citizen of the United States, residing at Jersey City Heights, in the county of Hudson 5 and State of New Jersey, have invented a new and useful Metal-Delivering Pump, of which the following is a specification.

This invention relates to a pump for delivering molten metal, which is capable of 10 general use but is particularly adapted for use in the casting of stereotype printing plates.

The principal objects of the invention are to provide a simple and convenient arrangement by which the metal can be pumped by 15 the use of compressed air; to provide means whereby the entire control of the pump can be provided for by means of a single lever; to provide means whereby the metal will be 20 kept in the pump until it is under considerable pressure and entirely fills the discharge outlet of the pump chamber and will then be discharged through the nozzle in a solid stream and thus prevent the preliminary discharge of small quantities of metal 25 before the main body is ready to be delivered; and to provide means whereby upon movement of the lever the metal-holding chamber will first be cut off from connection 30 with the outside air, thereafter connected with a source of air under pressure, and finally the metal will be released and allowed to flow out through the nozzle.

Reference is to be had to the accompanying drawings in which,

Figure 1 is a plan of a pump constructed in accordance with this invention;

Fig. 2 is a central sectional view of the same; and Fig. 3 is an enlarged elevation of 40 certain features thereof.

The drawing shows a metal pot A adapted to be filled with molten metal and provided with a metal pump body 10 having a chamber therein for receiving the molten 45 metal through a port at the bottom which is provided with a valve 11. An air pipe 12 is screwed into the top of the pump body or chamber 10 so as to connect the same with a source of compressed air from a pipe 15.

The connection of the pipes 12 and 15 is controlled by a valve 13 to the stem 17 of which an operating lever is attached. The upper end of the valve casing 18 has two openings, one of which is connected with the pipe 15 and the other 16 serves for leading the air 55 pressure out of the chamber 10.

The valve stem 17 has an arm 21 fixed thereon, operating between stops 22 and 23 cast on the valve casing. These stops regulate the extreme positions of the valve stem 60 and operating lever 14. A balance weight 24 is shown for bringing the lever back to the position shown in the drawing, after it has been operated.

The chamber 10 is provided with a port 65 25 at the bottom, opening into a discharge passage 26 which extends upwardly within the pot A to a position above the top of the pump body 10, or at least above the top of the level of molten metal in the pot A. This 70 passage 26 is really a part of the chamber 10. An outlet opening at the top of this passage is closed by a valve 27 which delivers into a nozzle 28 and is provided with a valve stem 29 having a projecting end 30 75 at the top. A spring 31 is provided to normally hold the valve closed. This projecting end 30 is in the line of motion of the lever 14 so as to be depressed thereby when the lever is depressed to its limiting position. It will be observed that the valve 27 is normally closed unless the same is depressed, and that the pressure of metal 80 against the valve 27 tends to hold it more tightly closed.

The operation of the device is very simple. The pressure of the metal from the melting pot normally raises the valve 11 so that it may enter the chamber 10 and passage 26 and rise in the latter to the level of the metal in the pot. To force the molten metal out through the nozzle 28, the lever 14 is depressed. The first effect of this is to cut off the chamber 10 from communication 90 with the outside air through the port 16. A slight further depression of the lever connects the pipes 15 and 12 and allows compressed air to enter the top of the chamber 95.

10. This tends to force the metal out of the chamber and, as the valve 11 is easily closed by excess pressure from above, all of the metal that is forced out goes into the 5 passage 26 and rises against the surface of the valve 27. This condition continues until the lever engages the projecting end 30 of the valve stem, when obviously the valve 27 is opened. Then the metal rushes out, 10 still under pressure, through the nozzle 28, and is delivered to the mold without any danger of a preliminary portion of the metal being delivered in small quantities. Upon releasing the lever, the weight draws 15 it back instantly to the position shown. The valve 27 is closed by its spring, connection between the pipes 12 and 15 is broken and the chamber 10 vented through the opening 16, thus allowing the metal to drop 20 back in the passage 26 and the metal from the pot to rise in the chamber 10.

Although I have illustrated and described only a single form of the invention, I am aware of the fact that many modifications 25 can be made therein by any person skilled in the art without departing from the scope of the invention as expressed in the claims. Therefore, I do not wish to be limited to all the details of construction herein disclosed 30 and described, but what I do claim is:—

1. In a metal pump, the combination with a chamber having a passage for receiving molten metal and an outlet above the maximum lever of the metal in said chamber, of 35 means for introducing compressed air into said chamber to force the metal into said outlet from the chamber, and a valve normally closing said outlet and adapted to be moved against the pressure of the metal in 40 the chamber while opening.

2. In a metal pump, the combination with a pot and a chamber therein for receiving molten metal therefrom, of a nozzle, a port 45 connecting the nozzle with said chamber and having a normally closed valve provided with a stem projecting therefrom for controlling the admission of metal from said chamber to the nozzle and through said port, and a means for controlling the admission 50 of pressure on the metal in the chamber to force it out past the valve and for pressing in the projecting end of the valve stem to open the valve and allow the metal to pass by.

3. In a metal pump, the combination with a chamber for receiving molten metal, of an outlet valve located and arranged to close by the pressure of metal thereon from said chamber, and means for forcing the metal 60 out of said chamber against said valve and for positively opening said valve to allow the metal to pass.

4. In a metal pump, the combination with a pot for molten metal, of a chamber therein

having an outlet passage extending upwardly from the bottom of said chamber, 65 means for introducing compressed air into the top of said chamber to force the metal up in the outlet passage, a nozzle connected with the top of said outlet passage above the top of the pot, and means for normally 70 closing the connection between the outlet passage and nozzle.

5. In a metal pump, the combination with a melting pot, and a metal receiving chamber therein having two ports, one communicating with the interior of the melting pot and the other constituting a discharge outlet, a valve for the first named port, an upwardly extending outlet passage connected with the second port, a nozzle at the top of 80 said outlet passage having a valve opening inwardly for controlling the flow of metal therefrom to the nozzle, means for normally closing said valve, said valve being adapted to be opened from the outside of the nozzle, 85 and means for introducing compressed air into the top of said chamber.

6. In a metal pump, the combination with a melting pot, and a chamber therein for receiving molten metal therefrom, of a nozzle on said pot having a valve provided with a stem projecting from the nozzle for controlling the admission of metal from said chamber to the nozzle, a pipe extending upwardly from said chamber, a compressed air 95 pipe, a valve adapted to connect said pipes, and a lever for operating said valve located in position to engage said valve stem when the lever is fully depressed and the valve in position to allow compressed air to flow from one pipe to the other.

7. In a metal pump, the combination with a melting pot, and a chamber therein for receiving molten metal therefrom, of a valve provided with a stem for controlling the discharge of metal from said chamber, a pipe extending from said chamber, a compressed air pipe, a valve adapted to connect said pipes, a counterweighted lever for operating said valve located in position to engage said valve stem when the lever is fully depressed and the valve in position to allow compressed air to flow from one pipe to the other, and means for limiting the motion of the lever.

8. In a metal pump, the combination with a melting pot, and a chamber therein for receiving molten metal therefrom, of a nozzle on said pot having a port connecting it with said chamber and a valve provided with a stem projecting therefrom for controlling the admission of metal from said chamber to the nozzle through said port, said valve opening inwardly toward the chamber, whereby the pressure of metal on the valve from the chamber will tend to close it, means whereby pressure can be applied to

the metal in the chamber to force it out past the valve, and a lever controlling said means located in position to engage the projecting end of the valve stem when the lever is moved to a position to cause pressure to be applied.

In testimony whereof I have hereunto set my hand, in the presence of a subscribing witness.

CONRAD NORDFORS. 10
